UNITED STATES PATENT OFFICE

ALFRED H. WILLETT, OF WEST ENGLEWOOD, NEW JERSEY, ASSIGNOR TO AMERICAN ARCH COMPANY, OF NEW YORK, N. Y., A CORPORATION OF DELAWARE

SIPHON ARCH BRICK

Application filed January 26, 1931. Serial No. 511,270.

This invention has reference to an improved form of brick for use in arches in fire boxes of locomotives equipped with internal water legs or siphons. These siphon walls are frequently found to be further apart or closer together than construction drawings call for and it is the primary object of my invention to provide a brick which may be easily and quickly fitted between siphons without impairing the provisions for holding it securely in position.

Another object of my invention is the provision of a brick which will permit of ready adjustment to variations in siphon spacings with the brick held securely in position.

A further object of my invention is the provision of a brick which may be easily centered between siphons and held securely in centered position.

The foregoing, together with such other objects as may hereinafter appear I obtain by means of a construction which I have illustrated in preferred form in the accompanying drawing, wherein

Figure 1 is a longitudinal section through a locomotive fire box and the arch illustrating the manner in which my improved brick is applied;

Figures 2, 3 and 4 are transverse sectional views showing my improved brick applied to siphons of different spacings; and

Figure 5 is a plan view of my improved brick.

The fire box here shown is provided with two longitudinal circulating elements 6 in the form of internal water legs or siphons. These siphons have a triangular portion 7, the upper edges of which are connected into and open through the crown sheet 8 and a forward extension 9 in the form of a tube which is connected to and opens into the throat sheet 10 below the flue sheet 15. The contour of the tube 9 is carried to the rear in the lower portion of the triangular part of the siphon in order to provide shoulders 11 therein for the support of arch bricks.

The fire arch extends upwardly and rearwardly from the throat sheet 10 and at its forward part is supported on the tubular ex-

tension 9 in the same manner as the usual tube supported sectional arch.

The rear portion of the arch, however, must be supported by the shoulders 11 on the lower part of the triangular portion of the siphon and the brick supporting surface is materially reduced as compared with the tubular portion 9, due to the fact that the flat plates 12 forming the walls of the triangular portion of the siphon are connected into what would be the upper part of the tube.

My improved brick is especially designed for use between such portions of the siphons. The brick 13 is of generally rectangular shape and has the lower end corners cut away at an angle to provide a sloping bearing surface 13' adapted to engage the shoulders 11 of the siphon. The brick is also provided with two small positioning lugs 14 at each end. These lugs engage the flat plates 12 forming the walls of the siphon, thus centering the brick between siphons and preventing it from shifting sidewise and dropping onto the fire.

It has been found that the spacing of the siphons frequently varies, however. In new locomotives the spacing between siphons may vary, owing to the inaccuracy of construction, and in locomotives in use the siphon spacing may vary somewhat, owing to warping of the plates. It is impractical for the railroads and builders to carry in stock bricks which would fit every variation of siphon spacing, and I have devised my improved brick to meet this condition.

The lugs 14 which engage the plates 12, while large enough to hold the brick securely in position, are of such size that they may be chipped away either partly or wholly in order to permit the brick to be used between siphons of different spacing. This can be clearly seen from Figures 2, 3 and 4 where the brick is illustrated in position under three different conditions of siphon spacing. In Figure 4 the brick fits without chipping the lugs. In Figure 3 the lugs have been slightly reduced in size, and in Figure 2 the lugs have been entirely chipped away. In all three positions the bricks will be held securely against shifting sidewise, and owing to the sloping character of the bearing surface the

bricks will engage the supporting shoulders 11 equally well in all positions.

In bricks without lugs, it is necessary for 5 railroads to carry in stock quite a large supply of different length bricks, or to materially alter the shape of the end of the brick by chipping the whole end when the bricks are 10 too large for the particular siphon spacing. There is also the danger that workmen, in 15 order to save time, may use a brick which is too small, i. e., one which would leave considerable space between the end of the brick and the side wall of the siphon, and in this case it is more than likely that the brick will 20 shift sidewise, allowing one end to clear the supporting shoulder 11, in which case the whole brick will fall through onto the fire.

My improved brick overcomes the foregoing difficulties and ensures rapid and accurate fitting of the bricks securely in proper position.

It will be understood, of course, that my improvement is not confined to the use of 25 two lugs at each end of the brick. There may be but one lug at each end or there may be more than two, depending on the particular 30 circumstances to be met. It is also unnecessary to have the positioning lugs at both ends of the brick and it may be desirable in some 35 cases to use the lug or lugs at one end only and confine all cutting of lugs to that end. It will also be understood that my improvement 40 may be embodied in the bricks extending between the side wall of a locomotive and the siphon, in which case it would probably be desirable to have the lugs at the end of the brick which is supported by the siphon, although the lug may be used in this case at either or both ends. My improvement will 45 be equally effective in any of the foregoing modifications.

I claim:

1. An arch brick for siphon equipped locomotive fire boxes adapted to be fitted between 45 and supported by the siphons, said brick having bearing surfaces at each end adapted to engage shouldered portions of said siphons and relatively small positioning lug means at each end of said brick adapted 50 to engage the siphon wall, said lug means being of such size as to be easily reducible to permit of ready adjustment of the brick to different siphon spacings.

2. An arch brick for siphon equipped locomotive fire boxes adapted to be fitted between 55 and supported by the siphons, said brick having bearing surfaces at each end adapted to engage shouldered portions of said siphons and relatively small positioning lug means 60 at each end of said brick adapted to engage the siphon wall, said lug means being of such size as to be easily reducible to permit of ready adjustment of the brick to different siphon spacings without impairing the support 65 engaging bearing surfaces of said brick.

3. An arch brick for siphon equipped locomotive fire boxes adapted to be fitted between and supported by the siphons, said brick having support engaging surfaces at each end thereof and relatively small positioning lug means projecting from an end of said brick and extending beyond the support engaging surface thereof. 70

4. An arch brick for siphon equipped locomotive fire boxes adapted to be fitted between and supported by the siphons, said brick having support engaging surfaces at each end thereof and relatively small positioning lug means projecting from an end of said brick and extending beyond the support engaging surface thereof, said lug means being readily reducible in size to permit of ready adjustment of the brick to different spacings of the support therefor. 75

5. An arch brick for siphon equipped locomotive fire boxes adapted to be fitted between and supported by the siphons, said brick having its lower end corners cut away to provide an inclined bearing surface at each end of the brick adapted to engage shouldered portions of said siphons and relatively small positioning lug means projecting from an end of the brick and extending beyond the bearing surface, the said lug means being adapted to engage a siphon wall 85 to retain the brick in position. 90

6. An arch brick for siphon equipped locomotive fire boxes adapted to be fitted between and supported by the siphons, said brick having its lower end corners cut away to provide an inclined bearing surface at each end of the brick adapted to engage shouldered portions of said siphons and relatively small positioning lug means projecting from an end of the brick and extending beyond the bearing surface, the said lug means being adapted to engage a siphon wall 100 to retain the brick in position and being of such size as to be readily reducible in size 105 in order to permit of ready adjustment of the brick to different tube spacings. 110

7. An arch brick for siphon equipped locomotive fire boxes adapted to be fitted between and supported by the siphons, said brick having bearing surfaces at each end adapted to engage shouldered portions of said siphons and relatively small positioning lug means at an end of said brick adapted to engage the siphon wall, said lug means being of such size as to be easily reducible 115 to permit of ready adjustment of the brick to different siphon spacings. 120

8. An arch brick for siphon equipped locomotive fire boxes adapted to be fitted between and supported by the siphons, said brick having bearing surfaces at each end adapted to engage shouldered portions of said siphons and relatively small positioning lug means at an end of said brick adapted to engage the siphon wall, said lug means 125 130

being of such size as to be easily reducible to permit of ready adjustment of the brick to different siphon spacings without impairing the support engaging bearing surfaces of said
5 brick.

9. An arch brick for siphon equipped locomotive fire boxes adapted to be supported at one end by the siphon, said brick having a support engaging surface at each end thereof
10 of and relatively small positioning lug means projecting from an end of said brick and extending beyond the support engaging surface thereof.

10. An arch brick for siphon equipped
15 locomotive fire boxes adapted to be supported at one end by the siphon, said brick having a support engaging surface at such end and relatively small positioning lug means projecting from such end of said brick and extending beyond the support engaging surface thereof.
20

In testimony whereof I have hereunto signed my name.

ALFRED H. WILLETT.
